HOD

Thomas W. Lee, Silverton, Ohio

Application October 22, 1948, Serial No. 55,946

3 Claims. (Cl. 294—69)

1

The present invention relates to hods for coal and the like and has for an object the provision of an automatic bottom-discharge hod that is particularly suited for manual tasks that are desirably performed in an easy and very cleanly fashion, for example the task of filling a domestic stoker with coal from the bin or coal pile.

Another object of the invention is to provide a hod for the stated purposes that effects its automatic bottom discharge of its contents when lowered onto an irregular or a yielding mass, but which will not discharge its contents when lowered to a plane floor or like surfaces.

Still another object of the invention is to provide a bottom-dumping hod that prevents the sifting or spilling of small or powdered particles from the bottom until the discharge door is opened.

A further object of the invention is to provide a hod of the class described that facilitates the handling of stoker coal and other small sized materials since said hod constitutes a scoop means whereby it may be filled from a pile of coal or the like without the use of a shovel, and allows the filled hod to be carried or to be rested on the floor without spillage of any of the fines or dusty particles and then emptied into a hopper or in another pile by merely lowering the hod to contact an irregularity within the hopper or pile and then withdrawing the hod to allow the contents to discharge through the open bottom.

These and other important objects are attained by the means described herein and exemplified in the accompanying drawings, in which:

Fig. 1 is a side elevational view of a hod embodying the invention.

Fig. 2 is a bottom plan view of the device of Fig. 1.

Fig. 3 is a cross sectional view taken on line 3—3 of Fig. 1.

The hod as exemplified in the drawings comprises a sheet metal body 10 formed in known fashion to tapered cylindrical shape and having a top bead 11 and a pair of bail mounting plates 12 secured at diametrically opposite sides whereby the hod is suspended from a suitable bail 13.

The bottom indicated generally as 14 may be constructed integrally with body 10 as shown, or it may be separately formed and attached in any suitable known fashion. In either case the bottom 14 has a discharge opening 15 bounded by the spaced parallel bottom edges 16 of flat convergently inclined portions 17 and 18, and by the edges 160 of narrow arcuate and inclined flange portions 19 and 20, which flanges connect

2

at their opposite ends with ends of edges 16. This arrangement of portions 17, 18, 19 and 20 provides, within the bottom interior of the hod, a series of inclined surfaces for facilitating complete discharge of the contents of the hod through discharge opening 15, and on the outside bottom of the hod a similarly shaped seat for a discharge door 21 which has an upwardly inclined peripheral flange consisting of opposed arcuate portions 22 and straight opposed portions 23 and 24. Suitable hinge means 25, attached in suitable fashion, serve to movably connect the portions 24 of the discharge door 21 with the flat portion 18 of the bottom 14 of the hod on the exterior thereof so, that when the door is open and the hod is elevated, the door may ultimately hang entirely free of opening 15 to permit complete gravitational discharge of the contents of the hod.

When the discharge door is secured in the closed position as shown it will be noted that the peripheral flange thereof seats in completely nested position over the depending portions of the bottom surrounding opening 21 of the hod, and that the top edge 26 of the door flange is disposed higher than the edges 16 and 160 that bound discharge opening 15. Thus closed, even the finest dust particles included in the contents of the hod will not escape from the hod when the discharge door is securely closed.

On the outside face of portion 17 of the bottom 14 there is secured a foot member 27, which is adapted on its inner face to serve as a latch keeper, for example as shown, an integral shouldered lug 28 may be provided for said purpose.

On the outside face of discharge door 21 there is provided a pair of foot members 29 and 30 which, in conjunction with foot 27 provide a three point support for the hod and serve to relieve the pressure of the weight of the contents of the hod when it is rested on said feet.

The feet 29 and 30 are herein shown as being part of a simple integral casting which includes a hand grip 31, and a pair of bars 32 which extend in supporting relation across the bottom of door 21 and are inclined toward each other and then terminate in a pair of upturned and slightly spaced lugs 33 which support the inclined flange 23 at the free edge of door 21.

The lugs 33 are drilled to receive a pivot pin 34 which supports an L-shaped latch arm 35 that has a nose 36 adapted to engage the latch keeper 28 and retain the door 21 in closed position as shown in Fig. 3.

An integral brace 37 connects the bars 32 of

the casting and prevents separation of the spaced lugs 33 in which the pivot pin 34 is supported. The casting is secured to discharge door 21 by screws 38 that are entered from the inside face of said door and fastened in threaded holes in the feet 29 and 30, and by another screw 38 which passes through door 21, and brace 37 and projects through the latter so that it serves as a depending pin on which a coil spring 39 is mounted so that the free end of said spring yieldably urges the latch arm to pivot into position wherein the nose 36 tends to engage in latching position.

The free end of arm 35 carries a plate 40 that is disposed intermediate the three supporting feet 27, 29 and 30 and not below the bottom of said feet when the discharge door is closed. When the plate 40 is pushed upwardly toward the door against the resistance of spring 39 the nose 36 of the latch is disengaged from keeper 28 and the door 21 may swing open under its own weight or the weight of the contents of the hod when the hod is lifted by the bail 13. This unlatching of the discharge door will be automatically effected if the hod is lowered in a place where the plate 40 may be engaged by any upstanding obstacle that enters the space between the three feet 27, 29 and 30 and effects the desired movement of the plate and its associated latch arm 35 relative to the door 21. The incidental act of resting the filled hod on the floor or any relatively flat and substantially unyielding surface will allow the door to remain in a latched position. The feet of the hod are of relatively small end section so that the weight of the filled hod is sufficient to cause the ends thereof to sink into a mass of coal in the stoker hopper when the hod is lowered into the partly filled hopper, thereby assuring positive unlatching of the door as the coal contacts the relatively large and extended area of plate 40. If the hopper be substantially empty, the then exposed portion of the stoker feed screw can be caused to engage the plate 40 on the hod and release the door 21. The normal use and operation of the hod for filling a domestic stoker hopper will be detailed because the user often wishes to keep both the basement and his clothes free of the soil of coal dust.

With door 21 latched, the user grasps the bail 13 of the hod with one hand and the grip 31 in the other hand and scoops the hod substantially full of coal from the coal pile.

If for any reason the door 21 is not initially closed and latched when the hod is lifted by the bail, a pressure on the hand grip will swing the door on its hinges 25 to a closed position and the latch nose 36 will ride up over the inclined face of lug 28 on leg 27. Arm 35 moves on its pivot and compresses spring 39 until the door 21 closes the opening 15, and the inclined flange on the door nests over the complementary inclined portion of bottom 14 of the hod. Spring 39 then exerts its force to swing the latch arm in the opposite direction to engage the latch nose 36 above the shoulder at the top of the lug 28 and causes the plate 40 to take the position shown in Figs. 1 and 2. The foregoing closing and latching of the door 21 after discharging the contents is accomplished quite easily by merely pulling in opposite directions on the bail 13 and hand grip 31.

After the door 21 is latched, the hand grip 31 is used to push the bead 11 into a pile of coal

75 for scooping the coal into the hod while the bail 13 guides the depth of the scooping action.

It will be noted that the bottom of the door 21 and of the hod do not become greatly soiled in use since these parts do not contact the coal during filling it as just described. In discharging the contents of the hod into a hopper the hod is desirably suspended from the bail 13, with the foot 27 disposed away from the user and the hand grip 31 closest to the user. When the hod is lowered and the latch released in the manner described, the subsequent lifting of the hod by said bail will allow the door to swing open on its hinges and the initial discharge of the contents will be in the direction of foot 27. As the hod is lifted progressively from the inside of the hopper the contents progressively pour out of discharge opening 15 with a minimum of scattering of dust. The door 21 will finally hang vertically from its hinges 25 entirely clear of opening 15 and even the lighter and finer dust particles will slide from the inclined inside peripheral face of the door flanges. The hand grip 31 and the bail 13 have both avoided contact with the coal in this normal use of the device so that soiling of the hands of the user is thus unlikely under the circumstances described.

The device may be advantageously used for various tasks that involve the handling of grain, feed materials, sand, loose dry soil and many other materials.

The invention herein is not to be considered as limited to the details of construction exemplified herein as they are subject to modification within the spirit of the invention and the scope of the appended claims.

What is claimed is:

1. In a hod the combination of an open topped body having a downwardly inclined bottom with a substantially centered discharge opening, a foot on the bottom adjacent one side of said opening and forming a latch keeper, a discharge door hinged exteriorly on said bottom adjacent the opposite side of said opening, an upwardly and outwardly inclined flange surrounding the door and adapted for complementary nesting on the exterior of said bottom surrounding the aperture, a latch member pivoted adjacent the free edge of said door and engageable in the keeper on said foot to retain the door in closed and dust tight relation on said bottom, a plate on said latch disposed substantially beneath the central area of the door and movable toward and away from the door for actuating the latch relative to said keeper, means yieldably urging the plate away from the door and tending to retain the latch in operative engagement with the keeper, and a pair of foot members on the door for sustaining the hod on a plane surface and precluding movement of the plate toward the door by such surface.

2. In a hod structure the combination of an open topped container body, a bail for carrying said body, a bottom on said body inclined downwardly and centerward and having a central discharge opening therewith, a latch keeper on said bottom adjacent one side of the opening, a door having a peripheral flange upwardly inclined for complementary nested seating on the exterior of the bottom surrounding said discharge opening, means hingedly connecting said flange at one side of the door with the exterior of said bottom adjacent the side of the discharge opening relatively opposite said latch keeper, means secured to and extending across and beyond the bottom of said

door and forming a hand grip at one end thereof adjacent the hinged side of the door, a latch member pivoted to said means and releasably engageable in said keeper, a plate on said member for movement toward said door for shifting the latch member to latch releasing position and a spring yieldingly resisting movement of the latch member from its latching position.

3. In a device of the class described the combination of a body having a bottom discharge opening, a door for said opening hinged to the body at one side of the opening, a support foot on the body disposed adjacent the opposite side of said opening and arranged and adapted intermediate its ends as a latch keeper, a rigid member secured across the bottom face of the door and providing, at one end thereof, an outwardly extending handle grip and a downwardly projecting pair of feet on the door adjacent its hinged mounted side, an L-shaped latch member pivotally suspended at one end thereof on the opposite end of said rigid member and presenting a latch nose engageable with the keeper on the support foot, spring means yieldably urging said latch

member about its pivotal mounting, and a plate on the free end of the latch member and disposed in spaced relation below the door and adapted to move the latch member to door-releasing position as it is lowered with the hood onto an elevated object passing between the aforementioned feet.
